CLEANING DEVICE.

1,099,544.

Specification of Letters Patent. Patented June 9, 1914.

Application filed June 21, 1912. Serial No. 705,020.

To all whom it may concern:

Be it known that I, LEONARD L. FERGUSON, a citizen of the United States, residing at 7037 Wabash avenue, Chicago, Illinois, have invented new and useful Improvements in Cleaning Devices, of which the following is a specification.

This invention relates to improvements in cleaning devices and more especially to a device including among its elements suction creating means and parts arranged for contact with the surface to be cleaned to withdraw the dust from the same, and also a rotating brush or other means for brushing the dust from such surface and collecting it in the interior of the device. The device may therefore be said to combine the operation of a carpet sweeper and also of a pneumatic cleaner and is designed in its ordinary operation to partake of the functions of both.

The device is designed to be propelled over the floor or other surface to be cleaned, being supported by wheels, and comprises in general terms a suction creating device which is actuated by the rotation of such wheels and a rotating brush which is driven from the forward pair of wheels. There is also included a dust box or suitable receptacle for collecting the dust which is drawn into the device with the entering currents of air and a suitable screen or air filter for separating the dust from the air which passes through the bellows or other suction creating device. A separate compartment or receptacle connected with the dust box incloses the brush and receives the dust from the latter, and the dust box is detachably secured to the rest of the apparatus in order that it may be conveniently removed for the purpose of emptying its contents.

A device embodying the principles of the present invention is illustrated in the accompanying drawings in which:

Fig. 1 is a view of the same partly in side elevation and partly in longitudinal vertical section. Fig. 2 is a bottom plan view. Fig. 3 is a horizontal section on the line A—A of Fig. 1. Fig. 4 is a view in side elevation of the forward end of the dust box showing the manner of supporting the same. Fig. 5 is a view of the same part in top plan view with a portion broken away to show one of the bearings for the brush shaft. Fig. 6 is a view of a part of the device from

the underside to show the driving wheels and their mounting.

As shown in said drawings the device comprises a suitable frame in the form of a platform 10, upon which are mounted suction creating devices in the form of bellows 12, the latter being covered by a housing or cover 14, and indicated here in dotted outline merely; being of the same form and construction as more particularly described in my co-pending application Number 703,408 filed June 13, 1912. The platform is supported at its rear on wheels 15, to which are connected by means of crank pins as shown, connecting rods 16, for the purpose of actuating the bellows; and the device is provided with a handle 17, and a handle rest 18, likewise of the form shown in my co-pending application, for the purpose of its propulsion upon the floor.

Below the platform 10 is arranged a detachable dust collecting receptacle or dust box 20, which is secured to the underside of the platform 10 by means of brace rods 22 extending downward from the platform and forming bearings for a cross shaft or rod 24, the latter being bent eccentrically through a part of its length as indicated at 25, whereby it may be rotated or turned to press against the bottom of the box and clamp it securely to the part above. The dust box is provided at its forward end with a thickened front wall 27, through which is cut a slot 28, such wall thereby forming a nozzle or dust collecting implement through which the air currents with their collected dust are drawn upward from the surface being cleaned and into the dust box; this operation being effected by means of the bellows above which exhaust the air from the dust box through openings in the platform 10 covered by a suitable screen or air filter 29 to separate the dust from the air and deposit it in the dust box.

At the forward part of the dust box and immediately to the rear of the front wall 27 a portion of the bottom, 30, is removed to accommodate a transverse horizontal brush 32 the latter being inclosed in a housing formed by the front wall 27, a parallel back wall 34, and a top wall 35, which is in the form of a flat shelf in the forward part of the dust box immediately below the opening of the slot 28 thereinto. The entering air currents pass over such shelf and de-

posit the dust to the rear of the wall 34, which prevents the dust from being spilled out. The ends of the transverse brush housing are partly closed by the side walls 38 of the dust box; but since the brush extends somewhat below the bottom 30 of the dust box, the brush housing is completed by means of end walls 39, which are secured flat against the outer surfaces of the side walls 38 and extend downward to nearly meet the floor when the device is resting on its wheels. The brush is rotated by means of friction disks 40 on the ends of its shaft 41, such disks engaging with driving wheels 43 which carry the weight of the forward part of the apparatus. The bottom of the brush housing is partly closed to the front and to the rear of the brush by means of hinged dust pans 46, 46, which extend transversely across the bottom of the housing and collect the dust which is swept up by its bristles. Each dust pan is set in an inclined position and is bent to form a wall 48, 48, lying tangential to the curved plane generated by the rotating brush and is also provided with triangular end walls 49 to prevent the spilling of dust.

The dust pans are pivoted on horizontal axes in order that they may be turned downward as indicated by the dotted lines in Fig. 1 for the purpose of dumping their contents, being shown as pivoted in the side members 39 by means of pivot rods or shafts 50, which pass through their end walls 49. A curved spring 53, which engages at its ends with the edges of the dust pans between the shafts 50 and presses outward on such edges, acts to retain the pans in either of their two positions as shown, such spring being pivoted at its center to a small lever 55 by means of which such center part may be raised or lowered in order to operate the dust pans; it being evident that when such ends are moved either above or below the plane of the two bearing shafts 50, the spreading apart of their lower ends will hold the dust pans in the position then assumed. The lever 55 is pivoted to the spring 53 by means of a pivot pin 57 which passes through a slot in the wall 39 to permit of the required raising and lowering of such pivot pin, and is fulcrumed at one end to the side of such wall 39 by means of a screw 58.

The brush shaft 41 is mounted in bearings 55 in the walls 39 but in such manner that its ends may be raised or lowered and may also be moved along a radius from the axis of the wheels 43. As shown in Fig. 5, each end of the shaft is mounted in a small bearing member or journal member 60, and these journal members are placed in recesses in the walls 39 of sufficient size to allow the journal members to move in all directions in the plane of such walls. Springs 62 act 65 to force the shaft toward the wheels and

provide the necessary frictional engagement between the latter and the friction disks on the ends of the brush shaft. Similar springs 63, placed below the bearing members, carry the weight of the forward part of the device 70 by means of balance links or equalizers 66, which are pivoted to the walls 39 at about their centers, as indicated at 68, and carry the wheels 43 at their forward ends; such wheels being mounted on short stub shafts 75 or pins 70 fixed in the forward ends of the balance links, and the brush shaft passing through openings 72 in the rear ends of the links. Each opening is elongated in the direction of the common radius through the wheel and friction disk in order to permit of the yielding pressure of the friction disk against the wheel by means of the springs 62 above described. It will be seen therefore that by means of the balance links 66, the 80 weight of the forward part of the apparatus is carried on the wheels 43 through the springs 63, and the parts are so proportioned and the apparatus so balanced that when the device rests upon a smooth hard surface, such as a hardwood floor, the tips of the brush bristles will just meet the surface to be cleaned and the cleaning nozzle 27 will lie slightly above such surface and permit the air to enter the air slot. When the device, however, rests upon a yielding surface, such as a carpet, the wheels 43 will sink into it until a part of the weight rests upon the nozzle 27, and such sinking or lowering of the wheels will correspondingly raise the 100 brush shaft at the other end of the balance links and cause the bristles to brush lightly over such surface; as would ordinarily be required in removing the dust from the nap of a carpet or similar fabric.

In operation the device is propelled over the surface to be cleaned whereupon the bellows 12 are actuated by the driving wheels 15 to create a suction through the nozzle 27, and at the same time the brush 32 is rotated to brush up the surface dust and deposit it in the dust pans 46; the equalizing links and the spring suspension of the forward part of the device acting to raise and lower the brush according to the requirements of the surface operated upon.

I claim as my invention:

1. In a cleaning device, suction creating means, a receptacle for dust, a suction nozzle adapted to assist in supporting said device, a wheel also adapted to assist in supporting said device, a rotative cleaning brush, and a link connecting said brush and wheel and centrally pivoted to said dust box to raise and lower them relatively to each other and to said nozzle according to the amount of load respectively carried by said wheels and suction nozzle.

2. In a cleaning device, suction creating means and a dust box detachably secured

thereto and having a cleaning nozzle communicating with its interior and suitably positioned to assist in supporting said device when the latter is at rest on a soft material such as a carpet, wheels supporting said dust box, a brush, and links connecting said brush and said wheels and centrally pivoted to said dust box to raise and lower them relatively to each other and to said cleaning nozzle ac-

cording to the amount of load respectively carried by said nozzle and said wheels.

In witness whereof, I have hereunto subscribed my name in the presence of two witnesses this 17th day of June, 1912.

LEONARD L. FERGUSON.
